UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

BOLSTER CONSTRUCTION.

No. 825,022.

Specification of Letters Patent.

Patented July 3, 1906.

Application filed July 24, 1905. Serial No. 270,998.

To all whom it may concern.

Be it known that I, ETHAN I. DODDS, a citizen of the United States, residing at Pullman, in the county of Cook and State of Illinois, 5 have invented certain new and useful Improvements in BolsterConstructions, of which the following is a specification.

My present invention is directed to improvements in bolster constructions for cars 10 and involves the use of smaller bolster-beams than have been usual in combination with connecting and spacing means at their central portions, which at the same time act as the bearing members.

15 My improvements permit of the use of comparatively large modern side bearings without unduly elevating the car or sacrificing strength.

20 In the accompanying drawings I have illustrated a construction embodying the principle of my invention.

Figure 1 represents an elevation of the same. Fig. 2 is an enlarged section on the line 2 2 of Fig. 1. Fig. 3 shows modified 25 forms of bolster-beams, and Fig. 4 is a view similar to Fig. 2 with some modifications.

The body-bolster comprises two spaced channel members 1 1, to the upper flanges of which is secured the plate 2, the main floor of 30 the car 3 resting thereon. The outer ends of the beams 1 1 are connected and spaced apart by means of cross members 4, and the central portions are connected, strengthened, and spaced apart by the downwardly-bellied member 5, having the integral upstanding flanges 6 riveted to the insides of the webs of 35 the beams 1. Transverse webs 7 connect the flanges 6 with the central bearing-sleeve 8, through which passes a king-pin 25. Horizontal outwardly-extending flanges 9 integral 40 with the members 5 are riveted to the lower flanges of the channel-beams 1.

The lower central portion of the part 5 constitutes a male bearing-plate 10, which 45 operates with the female center-plate bearing 17 of a plate 16, the latter, together with an underlying compression-plate 15, being riveted to the upper flanges of the channel-truck bolster-beams 13 and 14. Between 50 the latter is a strengthening and spacing member 18, which is in some respects similar to the member 5. It has the flanges 20 extending upwardly in contact with the insides of the webs of the truck-bolster beams 13 and

14 and riveted thereto. It also has the out-standing flanges 19 riveted to the lower flanges of the channel-beams 13 and 14. The bellied portion 18 has at its central part a king-pin bearing-sleeve 22, which is secured to the other portions of the member 18 by means of the integral upper and lower connecting-plate portions 23 and 24 and the webs 21.

It is evident that the invention may be embodied in bolsters having bolster-beams 65 of other forms than the channel-beams shown in Fig. 2. For instance, said bolster-beams might take the form of I-beams 11 or Z-beams 12 (shown in Fig. 3) or other standard rolled forms. In Fig. 4 I have illustrated a 70 structure similar to that shown in Fig. 2, but employing the Z-beams 12 in the body-bolster in lieu of the channel-beams 1, such a construction involving a slight modification of the reinforcing member 5 by the formation 75 of integral inwardly-extending grooved members 5* to receive the lower flanges of the Z-beams in lieu of the outwardly-projecting flanges 9 of Fig. 2.

Various other modifications in the details 80 of form and construction might be made by those skilled in the art without departing from the substance of the invention as defined in the following claims.

I claim—

1. In a bolster, the combination of two spaced members, and a connecting member having integral center-plate bearing, fastening, and king-pin bearing portions, substantially as described. 85
2. In a bolster, the combination of two spaced members, and a bellied connecting member having integral center-plate bearing, fastening, and king-pin bearing portions, substantially as described. 90
3. In a bolster, the combination of two spaced members and a bellied connecting member having integral center-plate bearing, fastening, and king-pin bearing portions, said fastening and king-pin bearing portions 100 extending between spaced members, substantially as described. 95
4. In a bolster, the combination of two spaced beams, each having a flange, and a connecting member having a center-plate bearing portion, integral flanges secured to the insides of the spaced beams, integral flanges riveted to the beam-flanges, and an 105

22
integral king-pin bearing portion, substantially as described.

5. In a car-bolster, the combination of spaced standard rolled beams, and a connecting member having a center-plate bearing portion, integral flanges riveted to the inner sides of the webs of the spaced beams, integral flanges riveted to the flanges of said beams, and an integral king-pin bearing portion, substantially as described.

6. In a bolster, the combination of spaced beams and a bellied connecting member riveted to the spaced beams and having an integral king-pin bearing portion, substantially as described.

15 7. In a car-bolster, the combination of spaced beams, a compression-plate and a bearing-plate riveted to said beams, and a connecting member riveted to said beams

and having an integral king-pin bearing portion, substantially as described.

8. In a car construction, a body-bolster comprising spaced beams, a connecting member riveted to said beams and having integral center-plate bearing and king-pin bearing portions, in combination with a truck-bolster comprising spaced bars, a bearing-plate riveted to said spaced bars, and coöperating with the aforesaid center-plate bearing portion, and a connecting member riveted 25 to said spaced bars and having an integral king-pin bearing portion, substantially as described.

ETHAN I. DODDS.
